UNITED STATES PATENT OFFICE.

WILLIAM E. CONGDON, OF WEST CHESTER, PENNSYLVANIA.

BAG-LOCK.

1,179,613.

Specification of Letters Patent. Patented Apr. 18, 1916.

Application filed November 20, 1914. Serial No. 873,227.

To all whom it may concern:

Be it known that I, WILLIAM E. CONGDON, a citizen of the United States, residing at West Chester, in the county of Chester and State of Pennsylvania, have invented certain new and useful Improvements in Bag-Locks, of which the following is a specification.

My invention relates to new and useful improvements in buttons and more particularly to a button adapted for use on an automobile pocket or similar device employing a flap for closing the same.

The primary object of the invention is the construction of such a button which may be locked in position whereby it cannot be operated by an unauthorized person.

A further object of the invention is the provision of a button of simple construction in which the parts are easily assembled and operated.

A still further object of the invention is the construction of a button adapted to be secured to the underside of the flap whereby it is impossible to manipulate the same except by inserting a key for unlocking.

With these and other objects in view the invention consists in the novel details of construction and arrangement of parts which will be more clearly understood from the following description and drawings, in which,

Figure 1 is a plan view showing the stud of the button. Fig. 2 is a face view of the button plate showing the key opening. Fig. 3 is a longitudinal vertical section on the line 3—3 of Fig. 1. Fig. 4 is a transverse vertical section on the line 4—4 of Fig. 1. Fig. 5 is a transverse section on the line 5—5 of Fig. 4. Fig. 6 is a detail of the key guide. Fig. 7 is a detail of the key, and Fig. 8 is a top plan view showing the button in locked position.

My improved button is primarily adapted for locking a flap to the body of a receptacle and as ordinarily constructed the button is secured to the receptacle and passes through an eye in the flap. By this arrangement access is gained to the button which extends through the eye. I have overcome this objection by constructing a button which is adapted to be secured to the flap and pass through an eye in the receptacle. By this construction the locking parts of the button are held within the receptacle and access

cannot be gained thereto without first unlocking the several parts.

In carrying out my invention I provide a plate 1 which is adapted to be secured to a flap in any suitable manner but preferably by means of rivets passing through the openings 2 and through the flap. The plate has a projection 3 formed thereon and a central bore is formed through the plate and projection. At the end of the projection is formed a circumferential flange 4 which overlies the central bore and the purpose of which will be presently described. The flange 4 is of such a width as to leave a central opening therethrough of less diameter than the central bore through the projection 3.

A sleeve 5 is received within the central bore through the plate and projection and said sleeve is provided on the outer end with an enlargement or bead, indicated at 6. The sleeve is provided with a plurality of vertically spaced openings, the purpose of which will be presently described. Within the sleeve is a plug 7 having a plurality of transverse openings therethrough as more clearly shown in Figs. 3 and 5 of the drawings. Operating in the transverse openings are the pin tumblers 8 which are pressed forward by means of the springs 9 which operate between the sleeve 5 and ends of the tumblers 8. The ends of the tumblers are adapted to extend through the vertically spaced openings in the sleeve 5, as shown in Figs. 3 and 5 of the drawings. A slot 10 is cut in the pin tumblers 8 near one end thereof and are adapted to receive the key for operating the bolts. A longitudinal bore is formed in the plug 7 and is adapted to receive the key guide 11 shown in detail in Fig. 6 of the drawings. This key guide is provided with a slot 12 into which the key is adapted to be inserted and is formed with the cutaway portions 13 which engage around the pin tumblers 8.

A slot 14 is formed in the projection 3 adjacent the central bore and is adapted to receive the ends of the pin tumblers 8 when the button is in locked position and which will be later set forth in detail. A projection 15 is formed on the inner end of the plug 7 and received upon the extension is a casting or button member 16 provided on the inner face with a circumferential flange 17 which is adapted to enter a circumferential

groove formed in the end of the projection 3. The button member is of the shape shown in Figs. 3 and 4 of the drawings, and the end of the projection 15 is flared, as shown at 18, 5 to secure the button 16 upon the projection.

A corrugated spring plate 19 encircles the projection 15 and is received between the flange 4 and the end of the plug 7. This spring holds the projection 17 on the button 10 16 in the groove in the end of the projection 3 at all times.

A key, is indicated at 20, for operating the pin tumblers 8 but I wish it distinctly understood that I do not limit myself to this 15 particular shape of key as it will be necessary to vary in shape so as to change each lock whereby only one key will operate a lock. The projection 3 and the button 16 are elliptical in shape and are adapted to 20 extend through an elliptical opening formed in a plate 21 which is adapted to be secured to the receptacle or pocket which the flap is to close. This plate 21 is shown in Fig. 8 25 of the drawings in which the button is shown in locked position.

Having fully described the detailed construction of my button it is thought that the advantages and operation will be clearly understood. As indicated in Figs. 1, 3, 4 and 30 5, the button is in its unlocked position ready to be inserted through the elliptical opening in the plate 21. When the projection passes through the elliptical opening the beaded ends 6 of the sleeve 5 is engaged 35 by the fingers and the sleeve rotated thereby rotating the elliptical button 16 so that it extends beyond the sides of the projection 3 and engages the plate 21, as more clearly shown in Fig. 8 of the drawings. The 40 pin tumblers 8 will enter the slot 14 and the button is then locked and cannot be removed without inserting a key to withdraw the tumblers. When it is desired to 45 unlock the button the key is inserted into the slot 12 formed in the key guide 11 and engages the slots 10 formed in the ends of the pin tumblers. By turning the key the tumblers are withdrawn from the slot 14 and the sleeve can then be turned to bring 50 the casting or button 16 into alignment with the projection 3. The members can then be withdrawn through the eye of the plate 21 and the flap opened to gain access to the receptacle.

55 In considering the advantages of my device it must be remembered that the button is secured to the flap and no parts are accessible until the flap is opened and when in locked position it is impossible to manipulate the several parts without first inserting the key for withdrawing the tumblers.

Having fully described the invention what I claim as new and desire to secure by Letters Patent is:—

65 1. A button comprising a stationary pro-

jection having a central bore therethrough and a slot adjacent the bore, a sleeve rotatably mounted in the bore and having a plurality of spaced openings, a plug mounted in the sleeve and provided with a plurality of transverse openings, and a longitudinal opening in communication with the transverse openings, tumblers having slots formed therein slidably mounted in the transverse openings and through the openings in the sleeve, a key guide rotatably mounted within the longitudinal opening and provided with cutaway portions adapted to receive the pin tumblers, a key adapted to be received in the key guide and engage the slots in the tumblers, and a head secured to the plug.

2. A button comprising a stationary projection having a central bore therethrough and a slot formed adjacent the bore, a flange 85 overlying one end of the bore, a sleeve rotatably mounted within the bore and provided with a plurality of spaced openings, a plug mounted in the sleeve and provided with a plurality of transverse openings in 90 alinement with the openings of the sleeve, tumblers slidably mounted in the transverse openings and through the openings in the sleeve, a projection formed on the plug, a head secured to the extension, and a spring 95 mounted between the ends of the sleeve and plug and flange.

3. A button comprising a stationary projection having a central bore therethrough, a slot formed adjacent the central bore and 100 a circumferential groove formed on one end, a sleeve rotatably mounted within the central bore and provided with a plurality of spaced openings, a plug mounted in the sleeve and provided with a plurality of 105 spaced openings in alinement with the openings in the sleeve, spring pressed tumblers carried in the transverse openings of the plug and extending through the openings in the sleeve, an extension formed on the plug, 110 a head secured to the extension, and a circumferential projection formed on the head and adapted to enter the circumferential groove in the end of the projection.

4. A button comprising a stationary projection having a central bore therethrough and a slot adjacent the bore, a sleeve rotatably mounted within the bore and having a plurality of spaced openings therein, a plug mounted within the sleeve and having a plurality of transverse openings in registration with the openings in the sleeve, spring pressed tumblers slidably mounted in the registering openings, said tumblers being provided with a transverse slot near one 120 end, a key guide, and means for operating the tumblers and adapted to engage in said slots.

5. A button comprising a stationary projection having a central bore therethrough 125

and a slot adjacent the bore, a sleeve rotatably mounted within the bore and having a plurality of spaced openings therein, a flange overlying the central bore, a circumferential groove in the projection, a plug mounted within the sleeve and having a plurality of transverse openings therein in registration with the openings in the sleeve, an extension formed integrally with the plug and having its free end flared, spring pressed tumblers mounted in the said openings, a head provided with a circumferential flange engag-

5

10

ing with the circumferential groove in the projection, secured on the said extension by the flared end and a spring between the 15 overlying flange, plug and sleeve, and means for operating said tumblers.

In testimony whereof I affix my signature in presence of two witnesses.

WILLIAM E. CONGDON.
